UNITED STATES PATENT OFFICE.

CHARLES A. KOEHLER, OF DECATUR, ASSIGNOR TO JULIUS L. KNIEPER, OF SAME PLACE, AND JOSHUA BARRICK, OF BLUE MOUND, ILLINOIS.

VAPOR-STOVE.

SPECIFICATION forming part of Letters Patent No. 281,375, dated July 17, 1883.

Application filed October 24, 1882. (No model.)

To all whom it may concern:

Be it known that I, CHARLES A. KOEHLER, a subject of the King of Bavaria, residing in the city of Decatur, county of Macon, and 5 State of Illinois, have invented certain new and useful Improvements in Vapor-Stoves, of which the following is a specification.

My invention relates to that class of gasoline-stoves in which two or more burners are used; 10 and it consists in connecting said burners with the water-reservoir in such a manner that each burner shall assist in heating the water.

In the drawings accompanying and forming a part of this specification, Figure 1 is an elevation of my device. Fig. 2 is a plan of the burners and reservoir with their connecting-pipes. Fig. 3 is an enlarged elevation of one burner and its accessories; and Fig. 4 is a bottom view of a burner, showing the disposition 15 of the boilers thereon.

a are burners connected with one another and with reservoir *e* by pipes *c*.

b are boilers arranged in pairs and formed

on the burners beneath their distributing-cups, in direct contact with the heat.

d is the pipe that supplies the burners with fluid.

The dotted lines in Fig. 1 indicate the portion of the stove-frame which supports pipes *c* *d* and reservoir *e*.

In operation, the water makes a complete circuit of the burners, and is, in part, heated by all.

I claim—

1. Boilers *b*, arranged in pairs, attached directly to the burners, and constructed to receive a pipe at both ends, in combination with said burners, substantially as shown and described.

2. Boilers *b*, burners *a*, pipes *c*, and reservoir *e*, all in combination, as and for the purpose set forth.

CHARLES A. KOEHLER.

Attest:

L. P. GRAHAM,

W. I. WALKER.
